United States Patent Office.

JAMES F. SAYER, OF MACOMB, NEW YORK.

Letters Patent No. 61,688, dated January 29, 1867.

IMPROVEMENT IN STAVE JOINTERS.

The Schedule referred to in these Letters Patent and making part of the same.

TO ALL WHOM IT MAY CONCERN:

Be it known that I, JAMES F. SAYER, of Macomb, in the county of St. Lawrence, and State of New York, have invented a new and useful Improvement in Stave Jointers; and I do hereby declare that the following is a full and exact description thereof, reference being had to the accompanying drawings making part of this specification:

Figure 1 is a perspective view of my improved apparatus.

Figure 2 is a cross-section of the knife stock.

Like letters of reference indicate corresponding parts in both figures.

My invention is an improvement on that patented by me August 21, 1866, (No. 57,387.) In that device I employed, in connection with the curved bed to which the stave is clamped, a swinging knife or shave, and a disconnected plane, which moved in a slot or groove, to joint the edges of the staves. My present improvement consists in a swinging plane instead of a disconnected one, employed in combination with the swinging knife and curved bed.

In the accompanying drawings, A indicates a bed, having a curved side, a, for fitting the stave to, and a level surface, b, for the sweep of the knife and plane. The bed is provided, midway on the back side, with a right-angled extension, D, and to this is pivoted, at l, the stock or handle m of the shave-knife B. Thus far the construction is the same as in my patent before alluded to. Instead of making my plane C independent and disconnected, and running in a slot or groove in the top of the bed, as in my first invention, I provide it with a stock or handle, P, pivoted at q. It thus forms a swing plane.

The operation will be readily understood. When the stave is secured in place on the bed, the knife B is swept over it from the centre each way to cut off the rough edge. When this is accomplished it is swung out of the way, as indicated by red lines, fig. 1, and the plane C is then swept over the edge of the stave from end to end, to joint it smooth. By thus following the curve of the stave, the swinging plane will not only cut much easier than the disconnected plane, but will also do its work better, by preventing splintering when running across the grain. It can also be held to its work much more readily than the disconnected plane, and there is no danger of its running from its work. This combination of the swing plane and knife with the curved clamping bed reduces the apparatus to a very simple and convenient form, and admirably adapts it to use in small shops where power is not available. In my former invention the cutting edges of the knife were formed as a part of the stock by simply thinning the same down in double-bevelled form. In thus forming the knife and stock of metal, it is very expensive. In my present invention I make the stock m of wood, simply cutting a throat, r, at the proper position on the under side, and across this throat I screw the double-edged knife B. This arrangement is very cheap, and is as effective in operation as if made entirely of metal.

What I claim as my invention, and desire to secure by Letters Patent, is—

The arrangement of the swinging plane C, double-acting knife B, and bed A, operating substantially in the manner and for the purposes specified.

In witness whereof I have hereunto signed my name in the presence of two subscribing witnesses.

JAMES F. SAYER.
